UNITED STATES PATENT OFFICE.

EDWARD J. BROOKS, OF EAST ORANGE, NEW JERSEY, ASSIGNOR TO E. J. BROOKS & CO., OF NEW YORK, N. Y.

FASTENING TIN-STRIP SEALS.

SPECIFICATION forming part of Letters Patent No. 296,124, dated April 1, 1884.

Application filed January 31, 1884. (No model.)

To all whom it may concern:

Be it known that I, EDWARD J. BROOKS, a citizen of the United States, residing at East Orange, in the State of New Jersey, have invented a new and useful Improvement in Fastening Tin-Strip Seals, of which the following is a specification.

My present invention is additional to inventions heretofore patented by me, and to those in particular which relate to fastening seals composed wholly of suitable "tin strips," having their ends interlocked with each other, and fastened by pressing or stamping at the sealing operation, so that any attempt to separate them shall cause a fracture of the metal.

This invention consists in a novel method of sealing or "fastening" such "tin-strip seals," hereinafter described and claimed, having for its object the greatest possible security against the fraudulent duplication of such seals, so as to deter and detect violations of the same.

Two sheets of drawings accompany this specification as part thereof. Figure 1 of these drawings is a face view of a preferred form of blank or seal-strip—"flat"—as it leaves the factory. Figs. 2 2^x represent sections of the same on the lines 2 2 and x x, respectively. Fig. 3 is an edge view of the same with its ends interthreaded, ready for pressing. Fig. 4 is an edge view of the same pressed; and Figs. 5 and 6 are face views, showing, respectively, the obverse and reverse of the pressed seal, illustrating the completion of the fastening operation. Fig. 7 is an edge view of a different blank interthreaded, and Fig. 8 is a like view of the pressed seal made therefrom fastened according to this invention, illustrating modifications. Fig. 9 is a side view of a seal-press such as I prefer to use in carrying out this invention, and Fig. 10 is a face view of its pair of dies.

Like letters of reference indicate corresponding parts in the several figures.

In carrying out this invention I employ a blank, shackle, or "seal-strip," A or A^x, for example, of suitable "tin" (tin-plate) having in one end one or more slots, s or s^x, and the other end, t or t^x, adapted to be threaded

therethrough, and to lie flatly over or upon 50 the slotted end. The tin may be any of the cheap grades commonly used for tin-strip seals, or of scraps of less "frangible" or brittle tin where greater strength is desirable, my present method of sealing or fastening the 55 seals rendering tin-strip seals of relatively ductile metal secure enough for practical purposes, by necessitating peculiar dies for re-fastening the same should a person be skillful enough to unfasten one without fracturing the 60 metal.

The preferred form of seal-strip illustrated by Figs. 1, 2, 2^x, and 3 has a pair of transverse slots, s s, formed in it and aligned with each other by a longitudinal raised or arched portion, a, near one extremity, to facilitate threading through said slots the narrow tongue formed by said end t. The tongue end t is threaded through the slots s s, as shown in Fig. 3, after passing the strip through the 70 sealing-staples S of a freight-car door, or the sealing-holes of its fastening, or in equivalent manner applying the same to baggage or the like which is to be sealed. It is then ready for pressing.

The seal-strip A^x shown "interthreaded" in Fig. 7 is similar in all respects to the one above described, save that its raised or arched portion a^x is transverse or parallel with its slots s^x, and it is provided with lips l l at the respective slots, to further facilitate threading the tongue end t^x through said slots in either direction. Said lips are readily formed, in cutting the slots s^x s^x, by the use of chisel-pointed punches or cutters, and may project 80 either at the convex side of the arch a^x, as shown in full lines, or at the concave side of the arch, as shown in dotted lines.

In carrying out this invention I further employ a seal-press, P, Fig. 9, which may be of 90 any approved kind possessing sufficient "power" and strength, and furnished with suitable dies. I have used and prefer for this operation a seal-press of the construction patented December 14, 1880, by E. J. Brooks & 95 Co., as assignees of Frederic Anthes, as set forth in Letters Patent No. 235,398, and have represented the same by way of illustration,

said press to be furnished with a pair of steel dies, D^a D^b, Figs. 9 and 10, constructed, respectively, with a cameo face bearing punching projections p p p and an intaglio face provided with matching depressions d d d, said projections and depressions being preferably two or more in number, and of sufficient extent jointly to fully cover or cross the slot or slots in the seal-strip A or A^x. An essential feature of said die projections and depressions is their construction in the form of numerals, as in the example, or letters, numerals and letters, or the like, so as to form indentations and projections in the shape of distinguishing-marks, capable of being readily described and identified, and of the requisite multiplication without duplicates. Another essential feature is their adaptation to impress both ends of the seal-strip from one and the same side of the seal, so that the projections of one end shall interlock with the indentations of the other end. They should taper and flare sufficiently to clear the metal easily, and the depressions d must admit the tin around the projections p. Said die D^a has been provided with a gage projection, g, and said die D^b with a matching recess, r, the former to facilitate locating the seal-strip properly between the dies. In some presses this may not be required.

Having interthreaded the ends of the seal-strip A or A^x by threading its tongue end (t or t^x) through its slotted end, as illustrated by Fig. 3, so that said ends lie flat or closely one against the other, as aforesaid, I apply thereto the press P, and by means of its dies D^a D^b impress both ends over and across its slots (s or s^x) as represented at m, Figs. 4, 5, 6, and 8, so as to close and mutilate the slots, as well as to thicken and crimp the tongue end and interlock the projections of one end with the indentations of the other, as aforesaid, whereby the separation of the ends without breaking or marring one or both, so as to insure detection, is effectively guarded against, while by making said indentations, or preferably the obverse projections, as shown in the form of numbers (777 in the example) or equivalent distinguishing-marks, their duplication is rendered so difficult as to be practically impossible, and their description, identification, and variation for different "roads" or users, are facilitated. Stamping over and across the slots, as aforesaid, or over and across one of the slots is considered essential to a reliable degree of security, and is therefore made an es-

sential element of my present method of fastening tin-strip seals. Said method of fastening the ends is peculiarly effective with the slots formed in arched portions, as in the preferred forms of seal-strip above described, as the arches are in this case flattened and the slots most effectively closed at the pressing operation.

The within-described seal-strips and dies, as well as the press shown by way of illustration, form no part of my present invention. Said seal-strip A^x, Figs. 7 and 8, forms the subject-matter of a previous application for a patent filed by me October 13, 1883, (Serial No. 109,304,) in favor of which it is hereby disclaimed. Interthreading the ends preparatory to pressing, together with the use of two (or more) slots, is illustrated at Figs. 18 and 19 in Patent No. 178,722, granted to me June 13, 1876, and connecting parallel transverse slots by a longitudinal raised or arched portion to facilitate interthreading, is illustrated at Figs. 9 and 9^x in Patent No. 258,278, for another of my inventions, dated May 23, 1882. The within-described seal-strip A, Figs. 1 to 3, inclusive, is therefore disclaimed in favor of these patents; and the broad idea of impressing either or both ends of a sheet-metal seal-strip, with retaining projections in the form of distinguishing-marks, is disclaimed, in view of my patented inventions set forth in Letters Patent No. 236,539, dated January 11, 1881, and No. 242,259, dated May 31, 1881, with said Patent No. 258,278.

Having thus set forth my said improvement in fastening tin-strip seals, I claim as my invention, and desire to patent under my present specification—

The improved method of fastening tin-strip seals herein specified, consisting in interthreading their ends by threading one end through slots in the other, bringing the ends together flatwise, one over or upon the other, and then stamping said ends over and across said slots or one of them, with indentations and projections in the shape of distinguishing-marks formed simultaneously in both ends from one and the same side of the seal, said projections on one end being thereby made to fit into and interlock with said indentations in the other end, substantially as shown and described.

EDWARD J. BROOKS.
